UNITED STATES PATENT OFFICE.

LEE A. FRAYER AND WILLIAM J. MILLER, OF COLUMBUS, OHIO.

ENGINE-DRIVEN BLOWER FOR EXPLOSION-ENGINES.

No. 813,204.

Specification of Letters Patent.

Patented Feb. 20, 1906.

Application filed January 11, 1905. Serial No. 240,670.

To all whom it may concern:

Be it known that we, LEE A. FRAYER and WILLIAM J. MILLER, citizens of the United States, residing at Columbus, in the county 5 of Franklin, in the State of Ohio, have invented certain new and useful Improvements in Engine-Driven Blowers for Explosion-Engines, of which the following is a specification.

Our invention relates to improvements in 10 engine-driven blowers wherein we provide a yielding gear-wheel mounted on the prime moving shaft and meshing with another gear-wheel mounted on a secondary shaft, which carries the blower at its outer end. This arrangement relieves the blower from the shock 15 due to the sudden starting or stopping of the engine, and inasmuch as the yielding gear is relatively larger than the gear with which it meshes the speed of the blower is thereby increased greatly beyond the speed of the engine.

Figure 1 shows a sectional view of our device and the manner of connecting the same to the main shaft. Fig. 2 is a plan view of 25 the cog-wheel with one-half removed. Fig. 3 is an enlarged view of the cog-wheel in vertical section. Fig. 4 is a view of the removable middle portion of the cog-wheel.

In the drawings, 1 and 2 designate blades 30 of the fan mounted upon the shaft 3, which carries upon its outer end a clutch 4, adapted to engage with a corresponding clutch 5 on the crank 6, used in starting the engine. Shaft 3 on its inner end carries a small cog- 35 wheel 7, adapted to mesh with the large cog-wheel 8, mounted, preferably, upon the crank-shaft of the engine. Cog-wheel 8 is so constructed that it may be separated along the circumference, thus dividing into similarly-constructed halves. Each half on its 40 interior side is provided with four projections or stops 9, 10, 11, and 12, each having an opening 13 therethrough. When the halves are placed together to form the complete cog-wheel, these openings register and 45 bolts may be inserted therein. The cog-wheel thus formed has a large opening 14 extending therethrough, into which is fitted a circular part 15, provided on its circumference with four projections 16, 17, 18, and 19,

each of which is designed to be positioned between two of the stops above mentioned upon the inner face of each of the halves of the cog-wheel described above. Between the projections of this inner portion of the wheel 55 and the stops spiral springs 20 are placed. This inner portion of the wheel contains an opening 21 to receive the crank-shaft 22, to which it is keyed, as shown at 23.

Assume that it is now desired to start the 60 engine. Crank 6 is applied to shaft 3 in the usual way and the motion induced in shaft 3 starts the fan, and by turning gear-wheel 7, which meshes with the large wheel 8, the engine is started. The power for operating the 65 fan is then transmitted from the engine through the large gear-wheel 8, small gear-wheel 7, and shaft 3. It is seen that the small gear-wheel will impart to the fan a higher rate of speed than that at which the 70 crank-shaft moves. The relative speed may be regulated by varying the size of the small gear-wheel at the desire of the operator.

The inner portion of the cog-wheel 8 is rigidly mounted upon the crank-shaft, and therefore moves with it. The outer portion of 75 said wheel has a movement independent of the inner portion, the limits of which are determined by the spiral springs and stops and projections. The range of movement is great 80 enough to relieve the shaft 3, carrying the fan, from the severe shock incident to quick starting or stopping of the engine.

It is obvious that when the engine is 85 quickly started or stopped there is more or less shock to be borne by the fan, and if the gear connection is rigid the shock is so great as to become a serious matter. We overcome this difficulty by the arrangement described above in connection with cog-wheel 90 8, in which the springs between the projections on the inner wheel and the stops on the cog-wheel take up the shock to a great extent, and in this way the stress upon the fan is relieved.

Having described our invention, what we 95 claim as new, and desire to secure by Letters Patent, is—

In an air-cooled explosion-engine, a secondary starting-shaft, a blower mounted there- 100

on, a small pinion on said shaft, a prime moving shaft, a relatively large cushioned gear-wheel thereon meshing with said pinion and adapted to form a yielding connection between said blower and said prime moving shaft, and whereby the speed of said blower is greatly accelerated.

In testimony whereof we affix our signatures in presence of two witnesses.

LEE A. FRAYER.
WM. J. MILLER.
